(57) CLAIM

The ornamental design for a pedicure spa, as shown and described.

DESCRIPTION

FIG. 1 is a perspective view showing the front, right side and top views of my new pedicure spa showing my new design; FIG. 2 is a perspective view showing the rear, left side and top views thereof;

FIG. 3 is a right side elevation view thereof; the left side elevation view being a mirror image;

FIG. 4 is a top plan view thereof;

FIG. 5 is a front elevation view thereof; and,

FIG. 6 is a rear elevation view thereof.

The features shown in broken line depict environmental structure only and form no part of the claimed design.
